UNITED STATES PATENT OFFICE.

NELS J. LUNDEEN, OF TACOMA, WASHINGTON.

FOLDING BRACKET.

Application filed November 29, 1921. Serial No. 518,497.

To all whom it may concern:

Be it known that I, NELS J. LUNDEEN, a citizen of the United States, residing at Tacoma, in the State of Washington, have invented certain new and useful Improvements in Folding Brackets, of which the following is a specification.

Many articles in daily use are frequently in the way and it is desired to withdraw them, but, at the same time, to make the storage in such manner that it would take a minimum amount of effort to bring the article into operative position. For instance in connection with typewriting machines, it is convenient to have them at one's desk, but when the machine is not in use it is objectionable to have it occupy the space which could otherwise be utilized, therefore it has been the habit of many to place a typewriting machine in a deep drawer of a desk, which necessitates lifting the typewriting machine from the drawer of the desk when it is to be used, and finding a suitable support for the machine. There are many other articles in daily use in connection with which the above considerations apply.

The object of my invention is to provide a desk drawer with a folding bracket to which is attached a shelf so that when the bracket is extended the shelf will be projected above the top of the drawer and the extreme end of the shelf will be projected beyond the edge of the drawer so that one edge of the shelf is supported by the edge 35 of the drawer while the other edge of the shelf is supported by the folding bracket. A typewriting machine, or other device, may be secured to this shelf so that when the device is not in use it with the shelf and bracket may be folded down into the drawer out of the way; with this and other objects in view my invention consists of the parts and combination of parts as will be herein-after more fully set forth.

45 In the drawings:

Figure 1 is a side elevation of a storage compartment partly in section with my invention attached and in stored position,

Fig. 2 is a detail sectional view of Figure 1, showing the attachment or bracket in extended position,

Fig. 3 is a sectional view of Fig. 2, looking in the direction of the arrows,

Fig. 4 is a longitudinal sectional view of

a compartment showing another embodiment of my bracket in full lines, in stored position and in extended position in dotted lines,

Fig. 5 is a similar view of still another embodiment of my invention, and

Fig. 6 is a top plan view of Fig. 5.

The reference numeral 1 designates a suitable compartment, such, for instance, as a drawer of a desk, in the bottom of which the lower end of the "U" shaped bracket member 2 is pivoted by means of suitable I-bolts or staples 3. 4 is another member of the bracket which is free from attachment to the compartment but is connected to the lower end of the cross arm 5 by means of a link 6, the link having loose pivotal connection with the bracket members, the bracket member 4 having a cross arm 7 similar to the cross arm 5 of the bracket member 2. The bracket members 2 and 4 cross each other, as clearly shown in Figure 2 of the drawing and are connected at their upper ends by means of a link 8, which is loosely pivoted at its ends to the upper cross arms of the bracket members 2 and 4. A shelf or leaf 9 is suitably secured to the link 8 between the upper ends of the bracket members 2 and 4 by means of screws and the like so that the shelf can be maintained in a horizontal position while it is being folded into and out of the compartment, whereby the article attached to the leaf may be maintained in a horizontal position during such movement of the leaf.

Another embodiment of my invention is shown in Figure 4, wherein 10 is the compartment and 11 is the shelf. The bracket in this embodiment comprises two members 12 and 13, which members are rectangular in shape having upper and lower and two side arms. The upper arms of the bracket members 12 and 13 are connected by means of the link 14, which link is loosely pivoted to said arms. The lower end of the bracket 13 is pivotally secured to the bottom of the compartment at 15 while the lower end of the bracket member 12 is free to swing backwardly and forward as the shelf and bracket are folded into and extended from the drawer, the lower end of the bracket member 12 abutting the lower front corner of the compartment, as shown in Figure 4, whereby it is prevented from moving forward, the

lower end of the bracket member 13 being prevented from moving rearward by means of its pivotal connection whereby when the parts are in these positions the two bracket members are held firmly in the extended position shown in dotted lines in Figure 4. The shelf 11 is designed to support any article.

In Figures 5 and 6 I have shown still another embodiment of my invention, which comprises two bracket members 16 and 17 which are rectangular in form, having two sides and top and bottom arms. The bottom arm of the bracket member 16 is pivotally secured at 18 to the bottom of the compartment, while the lower arm of the bracket member 17 is slidably mounted on the bottom of the compartment in guides 19. The upper ends of the bracket members 16 and 17 are secured together by means of the link 20, the connection between the link and the brackets being a pivotal one. To counter-balance the weight of the article placed upon the shelf 21 said shelf is pivotally connected to the upper arm of the bracket 16 and a coil spring 22 is provided which is anchored at one end to the front wall of the compartment and connected at its other end to the lower arm of the bracket 17 so that as soon as an upward lifting force is applied to the shelf 21 the spring immediately exerts its power, pulling the lower end of the bracket member 17 toward the front of the compartment, thereby assisting in elevating the shelf 21.

In folding the bracket and leaf 21 within the compartment the spring 23 connecting the lower arm of the bracket 16 with the upper arm of the bracket 17 exerts a downward pull thereby counter-acting the power of resistance of the spring 22, thus enabling one to lower the shelf and bracket within the compartment without jar, the spring 22 being under tension in the lowering movement.

What I claim is:

1. The combination with a compartment of a supporting leaf adapted to be moved

into and out of said compartment, a bracket having one arm thereof pivotally secured to 50 said leaf and to the bottom of said compartment and having its other arm slidably connected to the bottom of said compartment, and means connecting the upper ends of said arms and spacing them from each other. 55

2. The combination with a compartment of a supporting leaf therefor adapted to be moved into and out of said compartment, a bracket having one arm thereof pivotally secured to said leaf and to the bottom of said compartment and having its other arm slidably connected to the bottom of said compartment, means connecting the upper ends of said arms, and spring means connecting the upper end of said second named arm with the lower end of said first named arm. 60 65

3. The combination with a compartment having front, rear and side walls and a bottom of a supporting leaf adapted to be moved into and out of said compartment, a 70 bracket having one arm thereof pivotally secured to said leaf and to the bottom of said compartment and having its other arm slidably connected to the bottom of said compartment, means pivotally connecting the upper ends of said arms, and spring means normally urging the lower end of said second named arm toward the front wall of 75 said compartment.

4. The combination with a compartment 80 having front, rear and side walls and a bottom, of a supporting leaf adapted to be moved into and out of said compartment, a bracket having one arm thereof pivotally secured to said leaf and to the bottom of said compartment and having its other arm slidably connected to the bottom of the compartment, means connecting the upper ends of said arms, spring means normally urging the lower end of said second named arm toward the front wall of 85 said compartment, and spring means connecting the upper end of said second named arm with the lower end of said first named arm. 90

In testimony whereof I affix my signature. 95
NELS J. LUNDEEN.
